Primary Examiner — Jeffrey D Asch*Assistant Examiner* — Tracey J Bell(74) *Attorney, Agent, or Firm* — NSIP Law(57) **CLAIM**

We claim the ornamental design for an electronic device, as shown and described.

DESCRIPTION

This design patent application is a Continued Prosecution Application under 37 C.F.R. 1.53(d) of U.S. Design patent application Ser. No. 29/586,182, which was filed on Dec. 1, 2016.

FIG. 1 is a rear perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines in the figures depict portions of the electronic device that form no part of the claimed design. The dot-dash broken lines in the figures represent a boundary to the claimed design and form no part thereof.
